UNITED STATES PATENT OFFICE.

SAMUEL M. WILSON, OF EAST DURHAM, NORTH CAROLINA.

MAIL-CATCHER.

1,268,311.

Specification of Letters Patent. Patented June 4, 1918.

Application filed January 13, 1916. Serial No. 71,935.

To all whom it may concern:

Be it known that I, SAMUEL M. WILSON, a citizen of the United States, residing at East Durham, in the county of Durham 5 and State of North Carolina, have invented certain new and useful Improvements in Mail-Catchers, of which the following is a specification.

My invention relates to new and useful 10 improvements in a mail catcher.

The primary object of the invention is the provision of a device of this character which is simple and inexpensive in construction and which may be adjusted to receive 15 mail from trains traveling in either direction.

A further object of the invention is the provision of means for holding the catcher in adjusted position.

20 A still further object of the invention is the provision of means for catching the bag from the train and depositing it in a receptacle.

Another object of the invention is the 25 provision of means for holding the mail bag grabber open until struck by the bag at which time it is released and guides the bag into the receiving receptacle.

With these and other objects in view the 30 invention consists in the novel details of construction and arrangement of parts which will be more clearly understood from the following description and drawings, in which,

35 Figure 1 is a front view of the catcher with the several parts in position ready to catch the bag,

Fig. 2 is a top plan view showing the parts in position for catching the bag,

40 Fig. 3 is a fragmental top view, partly in section, showing the receiving receptacle and means for adjusting the same,

Fig. 4 is a perspective view of one of the arms for grabbing the bag, and

45 Fig. 5 is a fragmental vertical section, showing the means for holding the mail bag catcher in adjusted position.

In the drawings, the numeral 1 indicates a post which may be secured in the ground 50 or attached to the cross ties along the track.

A flange 2 is formed on the top of the post 1 and said flange 2 is provided with a rib 3 formed on the top thereof, the purpose of which will be presently described.

55 Circumferentially spaced pockets or recesses 4 are formed in the top face of the

flange 2, as are more clearly shown in Fig. 5 of the drawings and the purpose of which will be presently described. A rod 5 is secured in the post 1 and extends from the top 60 thereof and receives a sleeve 6 which is rotatable thereon and provided on the lower end with a flange 7 provided on the under face with a groove adapted to receive the rib 3 on the flange 2. Circumferentially 65 spaced openings 8 are formed in the flange 7 and are adapted to register with the sockets or recesses 4 formed in the upper face of the flange 7. A pin or peg 9 is secured to the post 1 by means of a suitable chain or 70 rope 10, and such pin or peg 9 is adapted to pass through the openings 8 and be received in the sockets or recesses 4. When in the position illustrated in Fig. 5 of the drawings, the pin or peg 9 will prevent rotation 75 of the sleeve 6.

A receptacle is adapted to be rotatably connected to the post 1 and this receptacle comprises the bottom slats 11, the vertical slats 12, and the bands 13, connecting the 80 vertical slats 12. A plurality of vertically spaced arms 14 are secured to the receptacle, as is more clearly shown in Fig. 3 of the drawing and said arms are provided with openings 15, the purpose of which will be 85 presently described. Plates 16 having openings therein are adapted to be secured to the arms 14 by means of the bolts 17 and nuts 18. The arms 14 and plates 16 are adapted to be received in vertically spaced grooves 90 formed in the post 1 whereby the receptacle is supported upon the post and may be rotated thereon. Recesses 19 are adapted to be formed in the post 1 and to register with the openings 15 formed in the arms 14 and 95 the openings formed in the plates 16. A pin or peg 20 connected to the plate 16 by means of a rope or chain 21 is adapted to pass through the openings in the arms or plate and be received in sockets or recesses 19 100 formed in the post 1. By this means the receptacle is held in adjusted position against rotation.

Arms 22 comprising a plurality of slats are adapted to be hinged to the sleeve 6 at 105 23, and the hinged ends of the arms are of the peculiar shape shown at 24, whereby they will fit around the sleeve when in closed position. Coil-springs 25 are connected to the sleeve 6 and to the arms 22, said coil-spring 25 being crossed, as is more clearly 110 shown in Fig. 2 of the drawings, whereby

they will normally tend to hold the arms in closed position. Arcuate shaped rods 26 are adapted to be secured to one of the arms 22 and pass through eyes 27 secured to the opposite arm. These arcuate rods 26 form guides for the arms when closing.

Sectional bars are adapted to be connected to each of the arms 22 and comprise the sections 28 hinged to the arms at 29 and the sections 30 hinged to the sections 28 and 31. In order to hold the arms 22 in spaced relation, the ends of the sections 30 are brought into engagement, as is more clearly shown in Fig. 2 of the drawings. These sectional bars are hinged in such a manner that they will spring inwardly when struck by the mail bag whereby the arms will be released.

Having fully described the details of construction it is thought that the operation and many advantages of my device will be clearly understood. It will be seen that I have provided a mail catcher which can be secured along the side of the track and which can be adjusted to receive the mail bags from trains traveling in either direction. When in position for receiving the bag, the parts are in the position shown in Figs. 1 and 2 of the drawings, the receptacle being beneath the arms 22. The sectional bars are in the position shown in Fig. 2 of the drawings, the ends of the sections 30 contacting thereby holding the arms 22 in open position against the tension of the spring 25. When the mail bag, which is hung from the car door, strikes the sectional bars, the ends of the sections 30 are disengaged and the springs 25 will then draw the arms 22 together whereby they will encircle the bag and direct it into the receptacle. The arcuate shaped rods 26 passing through the eyes 27 will guide the arms while closing. When it is desired to reverse the parts for catching the bags from a train traveling in an opposite direction, it is only necessary to remove the pin 9, whereby the sleeve 6 may be rotated upon the post. The pin 20 secured to the plate 16 can then be removed and the receptacle can be swung upon the post. When in the desired adjusted position the pins 20 and 7 are again placed in their positions and the parts are held against rotation.

Having fully described my invention what I claim as new and desire to secure by Letters Patent is:

1. A mail catcher, comprising a support, a pair of sleeves rotatably mounted on said support and placed one above the other, said lower sleeve having pockets formed in

the top thereof, said upper sleeve having a flange formed on its lower end and provided with openings registering with said pockets, a pin adapted to be passed through said openings for engagement with said pockets, a receptacle carried by said lower sleeve and mail engaging means connected to said upper sleeve and positioned above said receptacle.

2. A mail catcher comprising a support, a sleeve rotatably mounted on said support and having pockets formed in the top thereof, a rib formed on the top of said sleeve, a receptacle secured to the sleeve, a second sleeve having a flange on its lower end, said flange provided with a groove to receive said rib and equipped with a plurality of openings registering with said pockets, a pin adapted to be passed through said openings for engagement with said pockets, and mail engaging means connected to said sleeve and positioned above said receptacle.

3. A mail catcher comprising a supporting post a rotatable sleeve surrounding the lower part of said post, a receptacle secured to said sleeve, a second sleeve surrounding the upper part of post and rotatably supported on said first sleeve, mail engaging means connected to said second sleeve and adapted to be positioned above said receptacle, and means for locking said sleeves together so as to cause the same to revolve in unison about said support.

4. A mail catcher comprising a support having vertically spaced grooves and sockets formed adjacent the grooves, a receptacle, arms secured to the receptacle and encircling the support in the grooves, said arms provided with openings adapted to register with the sockets, a pin adapted to be received in the openings and sockets, a flange formed on the top of the support and having sockets therein, a sleeve rotatably mounted upon the support, a flange formed on the sleeve and provided with openings, a pin adapted to pass through the openings in the flange and be received in the sockets in the flange on the support, arms hingedly connected to the sleeve, springs connected to the sleeve and arms, eyes secured to one of the arms, and rods secured to the opposite arm and adapted to pass through the eyes.

In testimony whereof I affix my signature in presence of two witnesses.

SAMUEL M. WILSON.
